UNITED STATES PATENT OFFICE.

RAYMOND S. MERRIETT, OF SYRACUSE, NEW YORK.

ELECTROMAGNETIC APPLIANCE FOR RAILWAYS.

Application filed August 11, 1923. Serial No. 656,847.

To all whom it may concern:

Be it known that I, RAYMOND S. MERRIETT, a citizen of the United States of America, of Syracuse, in the county of Onondaga, 5 in the State of New York, have invented new and useful Improvements in Electromagnetic Appliances for Railways, of which the following, taken in connection with the accompanying drawings, is a full, clear, and 10 exact description.

This invention relates to an electric appliance for railways adapted to be used in connection with automatic brake operating systems of the class set forth in my pending 15 application filed August 11, 1923, Serial Number 656,848, and in any other relation where a primary electromagnet or coil is to be used as a part of the track equipment to cooperate with a secondary coil carried by 20 the train receiving current by induction from the primary coil in the operation of one or more translating devices on the engine or train.

The main object is to enable these primary 25 electromagnets or coils to be placed at suitable intervals along and beneath either or both rails in such manner as not to interfere with the magnetic circuit or free induction of the current from the electromagnet to the secondary coil on the train.

Another object is to provide each coil with 30 a case of insulating or non-magnetic material to protect it from the elements and contact with external objects, and at the same 35 time to enable the case with the primary electromagnet therein to be easily and quickly installed as a unit beneath the rail by securing of the case to an adjacent tie or other suitable support.

40 Other objects and uses relating to specific parts of the invention will be brought out in the following description.

In the drawings:

Figure 1 is a cross sectional view of a rail 45 and underlying case containing one of the primary electromagnets together with insulating blocks of wood or equivalent material applied to opposite sides of the web and covering the base flanges of the rail.

50 Figure 2 is a sectional view taken in the plane of line 2-2, Figure 1, showing the manner of securing the case or housing for the electromagnet to the tie and also showing the relative positions of the insulating blocks and electromagnet.

In order that my invention may be under-

stood, I have shown one of the rails as —A— of a railway track adapted to rest as usual upon ties between which are placed the electromagnets as —1—, preferably of the 60 horse shoe type except that its poles —2— and —2'— are extended laterally or in opposite directions from the opposite arms of its core and that the winding as —1'—, is around the intermediate portion of the core 65 poles.

The electromagnet is preferably inclosed in a suitable case or housing —3— of insulating or non-magnetic material which is secured by screws —4— or equivalent fastening means to the upright face of one of the ties —a— directly beneath the base flange of the rail —A—, thereby supporting the intermediate portion of the electromagnet —1— in a similar position directly 75 below the rail.

The core is supported within the casing upon suitable pins —5— while the ends of the winding or coil are brought into a cable —6— and extended outwardly through a 80 conduit —7— in one side of said casing for connection to any suitable source of electric energy and translating devices not necessary to herein illustrate or describe except that the electromagnet is adapted to be energized 85 by the passing of the train along the track and may be the "caution" magnet, "danger" or "reset" magnet described in my pending application previously referred to for the purpose of energizing by induction, the secondary circuits in the train for automatically effecting the operation of the engineer's brake valve or other device for applying the brakes.

The ends or poles —2— and —2'— of the 95 core of the electromagnet and adjacent ends of the case —3— extend some distance beyond the opposite edges of the base flange of the rail —A— to prevent short circuiting of the magnetic circuit and also to permit 100 induction from the energized electromagnet to the secondary coil and secondary circuit of the train as the secondary coil is brought into the field of the electromagnet by the movement of the train along the track.

105 As a further means for preventing short circuiting of the magnetic circuit of the electromagnet by the rail —A—, suitable insulating blocks —8— are secured by one or more bolts —9— to opposite faces of the 110 web of the rail between the head and base flanges thereof directly over the central por-

tion of the electromagnet and across the outer longitudinal edges of the base flange of said rail, but within the length of the poles —2— and —2'— so that when a coil 5 of the secondary circuit carried by the train is brought within the field of the magnet by the movement of the train along the track, the current will readily pass from the poles —2— and —2'— to the secondary coil which, 10 of course, would be arranged with its core or axis substantially parallel with the axis of the core of the electromagnet —1— or in the most suitable position for receiving flux from the pole pieces of the electromagnet.

15 I claim:

1. An electromagnetic appliance for railways comprising in combination with one of the rails, an electromagnet directly below and in proximity to the base of the rail, and 20 a housing of non-magnetic matter inclosing said magnet.
2. An electromagnetic appliance for railways comprising in combination with one of

the rails, an electromagnet directly below and in proximity to the base of the rail and 25 having the ends or poles of its core extending laterally some distance beyond opposite sides of the rail, and a housing of non-magnetic material inclosing said electromagnet.

3. An electromagnetic device, as in claim 30 1, in which blocks of insulating material are applied to opposite sides of the rail directly over the electromagnet.

4. An electromagnetic device, as in claim 35 1, in which the electromagnet is of the horse-shoe type and its poles extended horizontally in a plane above its intermediate portion, and the winding of the electromagnet is confined to the intermediate portion some distance from the horizontally extending poles. 40

In witness whereof I have hereunto set my hand this 2nd day of August 1923.

RAYMOND S. MERRIETT.
